UNITED STATES PATENT OFFICE.

CHRISTOPHER W. LEVALLEY, OF ST. PAUL, MINNESOTA.

SEEDER.

SPECIFICATION forming part of Letters Patent No. 338,987, dated March 30, 1886.

Application filed July 13, 1883. Serial No. 100,756. (No model.)

To all whom it may concern:

Be it known that I, CHRISTOPHER W. LEVALLEY, a citizen of the United States, residing at St. Paul, in the county of Ramsey and State of Minnesota, have invented certain new and useful Improvements in Seeders, of which the following is a specification, reference being had therein to the accompanying drawings.

Figure 1 is a rear elevation of the hopper of a seeding-machine containing my invention. Fig. 2 is a transverse section on line $x y$, Fig. 1. Fig. 3 is a transverse section showing a modification. Fig. 4 is a partial bottom view. Fig. 5 is a partial longitudinal section. Fig. 6 is a partial plan or top view. Fig. 7 is an elevation of a feed-tube. Figs. 8, 9, 10, 11 are detailed views.

In the drawings, $A A$ are the front and rear converging sides of the hopper. A' is the cover hinged to one of the sides, and A'' is one of the ends. The bottom of the hopper is formed of separable pieces of cast metal of peculiar form, which is to be hereinafter described.

In Fig. 2, $B B$ represent segmental portions of a hub, each provided with two radial flanges, $B' B'$, the inner portions of each segment being circular in form, so that when the parts are bolted together they shall clasp tightly a driving-shaft, D^2 , which extends the entire length of the hopper, and projects through one end thereof. Each of these radial flanges is provided near its end with a perforation adapted to receive a clamping bolt and nut, $b b'$, by means of which these flanges can be made to grasp tightly a flexible blade, C , the thickness of the blades being such as to permit the segments to be secured so closely together that their central portions shall grip the driving-shaft, while at the same time the blades shall be held firmly in position. Thus it will be seen that these parts $B B' C b b'$ constitute a feeding-wheel which can be adjusted longitudinally upon the feeding-shaft, and it will also be seen that this wheel can be readily applied to or removed from the shaft without taking the shaft from its bearings, whenever it is found desirable to do so.

Each of the metal sections of which the bottom is composed consists, essentially, of two flat wing-pieces, $D D'$, which converge and are joined at their lower ends by a transverse

plate, E , provided with perforations through which bolts b^2 pass into the lower edges of the sides A , as shown in Fig. 3. One of these flat wing-pieces, D , is provided at its outer widest end with upwardly-projecting perforated ears $d d$, through which screws c pass into the side boards, A , as indicated in Figs. 3, 5, and 6, or, when preferred, the opposite wing, D' , has its outer end shouldered and provided with an angular lip or flange, D^3 , which fits into a correspondingly-shaped recess or rabbet, D^4 , formed for its reception in the adjacent end of the wing D , thus locking the parts firmly together and forming a tight joint to prevent the escape of seed. Each of the wings is provided at its converging sides with projecting lips, preferably wedge-shaped in cross-section, which are seated in grooves formed for their reception in the sides $A A$ of the hopper, thus assisting to support the parts firmly in their desired relation and prevent the escape of seed.

e is an opening, preferably square, formed centrally in the bottom plate, E , and having the converging sides, so that the whole is surrounded by a comparatively sharp edge at the lower surface of the plate.

G is a downwardly-projecting annular flange cast in one piece with the bottom plate, E . This flange is not continuous, but is broken away upon its rear side, forming a throat, g . $g' g'$ are angular slots formed in the flange G and opening downwardly.

F is a gate pivoted at f to the under surface of the plate E . The form of this gate is shown plainly in Fig. 4, where it is represented in two positions, one full lines and one dotted lines. The end f' of this gate projects rearwardly, though the throat g extends beyond the rear wall A of the hopper and through a slot, h , in a carrier, H , mounted upon a gate-rod, I , to which it is attached by set-screw i . The walls at the ends of the slot h are beveled or rounded, as shown in Figs. 4 and 10, so as to insure their fitting closely upon opposite sides of the projecting end f' of the gate, while permitting the desired freedom of movement without clamping the parts.

$K K$ are supporting-brackets bolted to the rear wall A of the hopper and provided at their lower ends with circular seats, in which the gate-rod I is supported.

M is a gate-lever, pivoted at m to the rear wall of the hopper, and having its lower end slotted to receive a stud, m², which projects from a socket piece or hub, m⁴, surrounding the gate-rod I, to which it is adjustably secured by means of set-screw m⁵. The upper end of the gate-lever is arranged behind a slotted strap, M², secured to the hopper, the lever carrying a stud-bolt and thumb-nut, m³.

m⁶ is a binder attached to or cast in one piece with the lever in such position that its point travels in close proximity to the upper curved edge of the strap M², which latter is provided with a series of figures to indicate approximately the amount of seed sown to the acre under any of the various adjustments of the lever.

The driving-shaft D² rotates in bearings D¹ formed in upwardly-projecting lugs, each of which is cast in one and the same piece with one of the metal bottom sections, D D'. This shaft projects through the end wall A², and through a bearing, N, attached to the outer face of the end board.

N' is a collar secured to the shaft inside the end board, and N² is a sprocket-wheel secured to the driving-shaft by a set-screw, n, which passes through the sprocket-wheel hub, which abuts against the outer face of the bearing N, so that by means of the hub of the sprocket-wheel and the collar N endwise movement of the shaft is prevented.

In Fig. 3 I have shown the hub of the feed-wheel as being cast in two parts, O, which are divided on the line l. O' is a bolt passing through the hub-sections and the shaft on a line at right angles to the line l, thereby holding the two hub-sections together. The driving-shaft is provided with a slot through which the bolt O' passes, and o is a set-screw seated in one half of the hub, whereby the feed-wheel may be secured upon the driving-shaft and adjusted longitudinally. In this Fig. 3 the elastic blades C are secured to the radial wings O² by means of bolts o' and nuts o².

In Fig. 7 I have represented the feed-spout P, provided with a separator P', which is supported on the arm p, a short distance below the mouth of the tube, the upper surface of the separator being convex or cone-shaped, as is customary in this class of machines. The upper end of the tube is provided with two inwardly-projecting spurs, p², which are diametrically opposite each other, and is recessed 55 or cut away upon its rear side, as at, p'.

By an examination of Figs. 4 and 7 it will be readily understood that the tube can be suspended from the flange G by inserting the spurs p² in the angular slots g', thus constituting a "bayonet-joint;" and it will be readily seen that the relation of parts is such that the gate F may, when the set-screw i is released, be moved into such position as will admit of the tube being applied to flange, G, the 60 lever being moved to one end of the throat g and of the recessed portion p' of the tube; yet when the gate is in working posi-

tion the tube cannot be detached from the flange, because the recessed portion p' is not wide enough to permit the tube to be rotated 70 on the flange to such extent as will permit the spurs p² to be withdrawn from the slots g'.

I am aware that what are called "force-feed seeding-machines" have been constructed with discharge-openings below the hopper and 75 a series of separately adjustable valves or gates for regulating the size of the discharge-openings, the valves being connected to an oscillating rod, whereby after the adjustments have been made all the valves can be operated; 80 hence I do not claim such construction; but in those earlier machines the valves were not arranged to close or partially close the openings in the bottom of the hopper, because the sizes of these openings were never changed, 85 these openings communicating directly with the shells or casings of the force-feeding devices arranged below the hopper, the openings in these last-mentioned shells or casings being closed by valves which vibrate in vertical planes; whereas in my machine the mechanism which agitates the seed in order to facilitate its passage through the discharge-openings is arranged above the bottom of the hopper, and the openings in the hopper-bottom 90 are increased or diminished by the movement of the valves or gates, which latter are pivoted directly to the hopper-bottom and vibrate in horizontal planes when actuated by a rod, which also slides in a horizontal plane. 100

What I claim is—

1. In a seeding-machine, the combination, with the detachable sections having wings D D', of the seed-hopper sides provided with inclined grooves adapted to receive and support 105 the edges of the wings, substantially as set forth.

2. In a seeding machine, a hopper provided in the bottom with a series of discharge-openings, in combination with a series of horizontally-vibrating gates pivoted to the lower face of the hopper, a horizontally-sliding bar, and means for adjustably connecting each of the gates to the sliding bar, whereby each gate may be separately adjusted relative to its adjacent discharge-opening, and after such adjustment has been made the series may be operated simultaneously to regulate the sizes of all the openings through the hopper-bottom, substantially as set forth. 115

3. In a seeder, a wheel formed in sections divided on a line parallel with the axis of the driving-shaft, substantially as set forth.

4. In a seeder, a feed-wheel formed in sections divided on a line parallel with the axis 125 of the driving-shaft, in combination with flexible blades secured between the sections of the feed-wheel, substantially as set forth.

In testimony whereof I affix my signature in presence of two witnesses.

CHRISTOPHER W. LEVALLEY.
